UNITED STATES PATENT OFFICE

MARTIN EULE, OF SPANDAU, GERMANY, ASSIGNOR TO SIEMENS-SCHUCKERTWERKE GESELLSCHAFT MIT BESCHRÄNKTER HAFTUNG, OF SIEMENSSTADT, NEAR BERLIN, GERMANY, A CORPORATION OF GERMANY

DEVICE FOR IMPROVING THE HEAT ABSORPTION OF TUBULAR BOILERS WITH BOILER TUBES LOCATED IN THE RADIATION CHAMBER

Application filed September 14, 1926, Serial No. 135,450, and in Germany April 7, 1926.

My invention relates to a device for improving the heat absorption of tubular boilers with boiler tubes located in the radiation chamber.

It is well known that in such boilers the problem arises of transmitting, if possible, all the heat of radiation and sensible heat of the fuel to the tubes i. e. no heat should be consumed by the masonry which, when this condition is fulfilled, may be omitted almost completely. In attempting to solve this problem, ribs, gills or fins have been welded to the tubes. Gilled or ribbed tubes are, however, expensive in production and difficult in the assembly.

According to my invention the problem is solved, in a form simpler and by far cheaper than the prior art means, by bringing the boiler tubes in intimate contact with a plate which is a good conductor of heat and which absorbs the heat of radiation and the sensible heat of the furnace, as far as these have not already been absorbed by the boiler tubes, and transmits them to the boiler tubes by radiation and conduction and by making this attachment easily removable.

Embodiments of my invention are illustrated in the drawing affixed hereto.

These drawings represent in:

Fig. 1 a transverse section through one modification on the line *b*—*b* in Fig. 1^a.

Fig. 1^a a longitudinal section through the modification Fig. 1 on the line *c*—*c* in that figure,

Fig. 2 a longitudinal section through another modification, and

Fig. 2^a a transverse section through Fig. 2 on the line *a*—*a* in that figure.

Like numerals of reference indicate like parts in all the figures of the drawing.

Referring to Figs. 1 and 1^a, 1 are the tubes traversed by the medium to be heated. These tubes 1 are pressed against plates 2 which absorb a portion of the heat of the furnace.

As the tubes 1, resting on bolsters 6 which partly surround the tubes and are assumed to extend the entire length of the tubes are thus in intimate contact with the plates 2 and these plates are good conductors of heat, a portion of the absorbed heat will be trans-

mitted to the tubes 1 by conduction from the plates 2. Another part of the heat absorbed by the plates 2 is, furthermore, transmitted to the tubes by radiation. The tubes are tightly drawn against the bolsters by removable straps 4, locked by wedge-shaped pieces 5 from the outside, or by other suitable removable means of attachment, for instance by the shackles 7 as shown in Fig. 2.

Referring to Fig. 2 and the cross-section Fig. 2^a, it will be seen that a wedge-shaped piece 3 is located between plate 2 and tube 1 and takes the place of bolster 6 in Fig. 1. Compared with the direct contact of the tube with the plate this design has the advantage that on expansion of the system due to the absorption of heat the wedge 3 slides downward under the action of gravity and thus maintains permanently a good heat-conducting connection between plate 2 and the tube 1. The tubes may be held to wall 2 by any suitable means, for instance by shackles 7 bolted to plate 2 by bolts 4^a. These shackles as shown would be placed preferably near the ends of wedge bolsters 3, so that a nearly continuous heat convection contact is established along the whole length of each tube, whereby a similar heat transfer effect is attained as with the continuous bolsters 6 in Figs. 1 and 1^a.

Various modifications and changes may be made without departing from the spirit and the scope of the invention, and I desire, therefore, that only such limitations shall be placed thereon as are imposed by the prior art.

I claim as my invention:

1. Means for increasing the heat transfer to tubes in tubular boilers or the like, comprising a good heat conducting fire box wall on the heat exposed face of which the tubes are disposed, means for holding said tubes against said wall, and wedge-shaped elements partly surrounding said tubes and being inserted—with the tapered end downward—between the tubes and the wall face and serving as bolsters for the tubes and tending—by dropping—to maintain an intimate heat transfer relation when the heat expansion moves the tubes away from the wall.

2. Means for increasing the heat transfer to tubes in tubular boilers or the like, comprising a good heat conducting fire box wall on the heat exposed face of which the tubes are disposed, heat conducting bolsters on said wall partway surrounding said tubes and on which the tubes rest, means for holding the tubes against the bolsters and means for insuring continuance of intimate contact of the tubes with said bolsters when the heat expansion moves the tubes away from the wall.
- 10 In testimony whereof I affix my signature.

MARTIN EULE.
